UNITED STATES PATENT OFFICE.

WARREN COLLINS, OF COLLEGE POINT, NEW YORK, ASSIGNOR TO STAMFORD GAS STOVE COMPANY, OF STAMFORD, CONNECTICUT, A CORPORATION OF NEW YORK
GAS-HEATER.

1,074,312.

Specification of Letters Patent.

Patented Sept. 30, 1913.

Application filed November 23, 1901. Serial No. 83,376.

To all whom it may concern:

Be it known that I, WARREN COLLINS, of College Point, Long Island, in the county of Queens, in the State of New York, have 5 invented new and useful Improvements in Gas-Heaters, of which the following, taken in connection with the accompanying drawing, is a full, clear, and exact description.

My invention relates to a gas heater of 10 convenient form to be used in all ordinary situations, of which the essential features are a burner, in which the air and gas are thoroughly mixed burning with a blue flame, a ring arranged around the burner slightly 15 to confine the flame, promoting the combustion, a dome or drum supported on the ring above the burner and acting as a combustion chamber to confine the mixed air and gas, and to insure practically perfect com- 20 bustion and the heating of a large amount of air, and a cone preferably of clay or other refractory material, having its point projecting downwardly adjacent to the flame, whereby the flame is divided, the 25 cone instantly heated, and the carbon and other products consumed as far as possible; the dome and cone may be used in combination with any other suitable burner.

My invention will be understood by refer- 30 ence to the drawing herewith in which the figure is a vertical sectional view of a stove constructed in accordance with my invention.

In the drawing, 1 indicates the standard 35 of suitable form carrying the burner 3, which may be a pipe substantially of the form here shown, made of cast metal having the enlarged or flaring intake 4, with which communicates the nozzle 5 on the gas 40 pipe 6 having controlling key 7, whereby the air and gas are thoroughly mixed and conducted to the enlarged burner portion 9 covered with the gauze cap 10, surrounded by ring 11, provided with lugs 12 to engage 45 with cap and clamped on burner by set screws 13, leaving a small space 14 between the ring and the burner for the admission of a small amount of air around the flame to promote combustion within the ring, 50 somewhat confining the flame and directing it upwardly and at the same time protecting it from the outer cold air. The ring 11 is provided with integral arms 15 on which is supported the shell 16 having an open base,

a limited number of perforations 17, 18 re- 55 spectively around its side and in its top; this drum or shell may be cast or formed of any suitable material giving sufficient firmness for the purpose for which it is applied and to sustain the rod 21, on which is carried by means of nuts 22, 23 the cone 24, having its point arranged to extend downwardly into the flame to separate and spread it. The cone may be solid or hollow 60 and of any suitable material, preferably 65 clay or other refractory non-conducting material, to resist the intense heat the cone becoming very hot, maintains the temperature and promotes combustion.

By my construction of burner a large 70 amount of air is intimately mixed with the gas without cooling the flame, so that the degree of combustion is high and the efficiency great, the largest amount of air being heated in proportion to the fuel consumed and practically perfect combustion obtained. Heretofore the great objection to blue flame gas heaters has been the imperfect combustion and the escape of some of the unconsumed gas.

Having thus described my invention, what I claim and desire to secure by Letters Patent is:

1. In a gas heater, the combination with a gas burner, of a single shell arranged over 85 the burner and having its lower edge substantially level with the burner, said shell being entirely open and unobstructed in its interior except for the cone and having an open bottom and perforations in its side and 90 top, and an inverted cone of refractory material arranged in the shell with its apex adjacent to and above the burner.

2. In a gas heater, the combination with a gas burner, of a single metallic shell ar- 95 ranged over the burner and extending sub- stantially level with the burner, said shell having an open and unobstructed interior except for the body of refractory material and having an open bottom and perfora- 100 tions in its side and top, and a body of refractory material arranged immediately above the flame to promote combustion.

3. In a gas heater, the combination with a burner having an enlarged tube to receive the air mixed with gas, a gas inlet adjacent 105 to the outer end of said tube, an enlarged flat burner at the upper end of the tube, a

gauze top to said burner, a ring surrounding the burner, means to secure the ring on the burner and to retain the gauze top in place, integral arms on the ring, a shell supported on the arms above and surrounding the burner, said shell having an open base and perforations in its sides and top, and a cone supported in said shell and arranged with its point extending downwardly adjacent to the center of the flame.

4. In a gas heater, the combination with a gas burner, of a single shell arranged over the burner, having a substantially open bottom and a substantially closed top, and sides provided with a limited number of openings toward their upper portion, so as to retard the escape of the heat, said shell being entirely open and unobstructed in its interior except for the cone, and an inverted cone of refractory material arranged in the shell with its apex adjacent to and above the burner, said cone being adapted to be superheated and retain the heat, promoting combustion.

5. In a gas heater, the combination with a suitable standard, of a suitable burner having an enlarged burner portion; means for supplying mixed air and gas to the burner, a gauze top fitted to the enlarged burner portion, a ring of slightly larger diameter surrounding and extending upwardly above said burner portion and leaving a narrow annular space between it and said burner portion for the admission of a limited amount of air, integral lugs on the ring engaging with the gauze top, set-screws on the ring engaging with the burner, integral arms on the ring, a single interiorly open shell supported on said arms having an open base and perforations around its side and in its top, and an inverted cone of refractory material suspended on the shell and having its apex arranged adjacent to the burner.

6. In a gas heater, a suitable burner having in combination a central, tubular portion, a flaring portion at one end of said tubular portion forming an enlarged, open intake end, a gas nozzle arranged adjacent to said open end to direct the gas thereinto, a flaring, enlarged burner portion at the opposite or outlet end of the tube, said burner portion being vertically arranged, a perforated cover forming a flat top to the burner portion, a ring of slightly larger diameter than the burner portion arranged around said portion so as to leave an annular space between them, said ring extending a short distance below the top of the burner portion and a short distance above said top, means to secure the ring on the burner, an inverted clay cone above the burner with its apex downwardly arranged to extend into the flame when burning, and a suitable support for the parts.

7. A gas heater composed of a suitable

burner, a suitable support therefor, a ring of slightly larger diameter than the burner arranged to surround and be supported on the burner, a single enlarged shell, having an open base and upper openings, supported on the ring and arranged to extend around and over the burner, and an inverted cone supported in the said shell and having its tip arranged adjacent to the upper portion of said ring.

8. In a gas heater, the combination with a suitable standard, of a suitable burner supported thereon having an enlarged burner portion, means for supplying mixed air and gas to the burner, a ring of slightly larger diameter surrounding and extending upwardly above said burner portion and leaving a narrow annular space between it and the burner portion, means to support the ring on the burner portion, a single, enlarged shell having an open base and perforations in its upper portion, means to support said shell on the ring, and an inverted cone of refractory material suspended in the shell and having its apex arranged adjacent to the upper margin of said ring.

9. In a gas heater, the combination with a suitable standard, of a burner supported thereon having a smaller tubular portion and an enlarger burner portion, means for introducing air and gas into the burner tube at the opposite end from the burner portion, a ring of slightly larger diameter surrounding and extending above said burner portion, means for detachably securing said ring on the burner portion, integral arms on the ring, and a single, enlarged shell having an open base and perforations in its upper portion supported on said arms and having its base arranged substantially on a level with the burner portion.

10. The combination in a gas heater, of a burner having a tubular portion provided with an open outer end and having an enlarged burner portion at its inner end, a perforated top on the inner end, a ring of slightly larger diameter than said inner end, clamped around thereto and extending above and below the perforated top, means to introduce gas mixed with air in the open end and a suitable standard for the parts.

11. In a gas heater, the combination with a suitable standard, of a gas burner supported on the standard, a ring of slightly larger diameter than the burner supported on the burner to leave an annular air space between the ring and the burner, a single shell supported above the burner to cover and inclose the burner, and a body of refractory material supported in the shell above and adjacent to the burner, said shell having openings in its sides and top.

12. In a gas heater, the combination with a suitable standard, of a tubular burner supported thereon, said burner being bent at an

angle so that its inner portion is arranged substantially vertically and its outer portion substantially horizontally and having a flaring mouth at both its inner and outer ends, of a gas nozzle arranged adjacent to the outer mouth to direct the gas thereinto, a perforated cap over said inner mouth, a metallic shell suitably supported over said inner mouth, and a body of refractory ma-

terial supported in the shell immediately above said inner mouth and adjacent thereto.

In testimony whereof, I have hereunto signed my name.
